CLAIM

The ornamental design for a hydrofoil board as shown and described.

DESCRIPTION

FIG. 1 is a top perspective view of a hydrofoil board in accordance with my new design;

FIG. 2 is a bottom perspective view thereof;

FIG. 3 is a rear view thereof;

FIG. 4 is a front view thereof;

FIG. 5 is a right-side elevation view thereof;

FIG. 6 is a left-side elevation view thereof;

FIG. 7 is a top view thereof; and,

FIG. 8 is a bottom view thereof.

The broken lines shown illustrate portions of the hydrofoil board and form no part of the claimed design. The dash-dot lines represent bounds of the claim and form no part of the claimed design.

1 Claim, 8 Drawing Sheets(56)
